(57) **ABSTRACT**

A multilayer coil component includes a multilayer body formed by stacking a plurality of insulating layers in a length direction and that has a built-in coil, and a first outer electrode and a second outer electrode that are electrically connected to the coil. The coil is formed by a plurality of coil conductors stacked in the length direction being electrically connected to each other. The first and second outer electrodes respectively cover at least parts of first and second end surfaces. A stacking direction and a coil axis direction are parallel to the first main surface. A length of a region in which the coil conductors are arranged in the stacking direction is from 85% to 95% of a length of the multilayer body. A distance between coil conductors adjacent to each other in the stacking direction lies in a range from 12 μ m to 40 μ m.

MULTILAYER COIL COMPONENT**CROSS-REFERENCE TO RELATED APPLICATION**

This application claims benefit of priority to Japanese Patent Application No. 2019-097641, filed May 24, 2019, the entire content of which is incorporated herein by reference.

BACKGROUND**Technical Field**

The present disclosure relates to a multilayer coil component.

Background Art

As an example of a coil component, Japanese Unexamined Patent Application Publication No. 2017-212372 discloses a coil component in which the stacking direction and the coil axis are both parallel to the mounting surface of the coil component.

In the coil component disclosed in Japanese Unexamined Patent Application Publication No. 2017-212372, an element body that includes a coil-shaped conductor part includes a first part, a second part, and a third part that are sequentially arranged in a direction parallel to a center axis of the coil. The glass content of the second part is higher than that of the first part and the third part, and the coil component has good characteristics in a high-frequency band located at around 10 GHz. However, in response to the increasing communication speed and miniaturization of electronic devices in recent years, it is demanded that multilayer inductors have satisfactory radio-frequency characteristics in higher frequency bands (for example, a GHz band located at frequencies greater than or equal to 60 GHz). There is a problem with the coil component disclosed in Japanese Unexamined Patent Application Publication No. 2017-212372 in that the radio-frequency characteristics of the coil component are not satisfactory in a band located at frequencies greater than or equal to 60 GHz.

SUMMARY

Accordingly, the present disclosure provides a multilayer coil component that has excellent radio-frequency characteristics.

A multilayer coil component according to a preferred embodiment of the present disclosure includes a multilayer body that is formed by stacking a plurality of insulating layers on top of one another in a length direction and that has a coil built into the inside thereof; and a first outer electrode and a second outer electrode that are electrically connected to the coil. The coil is formed by a plurality of coil conductors stacked in the length direction together with the insulating layers being electrically connected to each other. The multilayer body has a first end surface and a second end surface, which face each other in the length direction, a first main surface and a second main surface, which face each other in a height direction perpendicular to the length direction, and a first side surface and a second side surface, which face each other in a width direction perpendicular to the length direction and the height direction. The first outer electrode covers at least part of the first end surface. The second outer electrode covers at least part of the second end

surface. A stacking direction of the multilayer body and a coil axis direction of the coil are parallel to the first main surface. A length of a region in which the coil conductors are arranged in the stacking direction lies in a range from 85% to 95% of a length of the multilayer body. A distance between coil conductors that are adjacent to each other in the stacking direction lies in a range from 12 μ m to 40 μ m.

According to the preferred embodiment of the present disclosure, a multilayer coil component can be provided that has excellent radio-frequency characteristics.

Other features, elements, characteristics and advantages of the present disclosure will become more apparent from the following detailed description of preferred embodiments of the present disclosure with reference to the attached drawings.

BRIEF DESCRIPTION OF THE DRAWINGS

FIG. 1 is a perspective view schematically illustrating an example of a multilayer coil component according to an embodiment of the present disclosure;

FIG. 2A is a side view of the multilayer coil component illustrated in FIG. 1, FIG. 2B is a front view of the multilayer coil component illustrated in FIG. 1, and FIG. 2C is a bottom view of the multilayer coil component illustrated in FIG. 1;

FIG. 3 is a sectional view schematically illustrating an example of the multilayer coil component according to the embodiment of the present disclosure;

FIG. 4 is an exploded perspective view schematically illustrating the state of insulating layers constituting the multilayer coil component illustrated in FIG. 3;

FIG. 5 is an enlarged sectional view of a region where coil conductors are connected to each other;

FIG. 6 is a diagram schematically illustrating a method of measuring the transmission coefficient S21; and

FIG. 7 is a graph illustrating the transmission coefficients S21 of test pieces manufactured in examples.

DETAILED DESCRIPTION

Hereafter, a multilayer coil component according to an embodiment of the present disclosure will be described. However, the present disclosure is not limited to the following embodiment and the present disclosure can be applied with appropriate modifications within a range that does not alter the gist of the present disclosure. Combinations consisting of two or more desired configurations among the configurations described below are also included in the scope of the present disclosure.

FIG. 1 is a perspective view schematically illustrating an example of a multilayer coil component according to an embodiment of the present disclosure. FIG. 2A is a side view of the multilayer coil component illustrated in FIG. 1, FIG. 2B is a front view of the multilayer coil component illustrated in FIG. 1, and FIG. 2C is a bottom view of the multilayer coil component illustrated in FIG. 1.

A multilayer coil component 1 illustrated in FIGS. 1, 2A, 2B, and 2C includes a multilayer body 10, a first outer electrode 21, and a second outer electrode 22. The multilayer body 10 has a substantially rectangular parallelepiped shape having six surfaces. The configuration of the multilayer body 10 will be described later, but the multilayer body 10 is formed by stacking a plurality of insulating layers on top of one another in a length direction and has a coil built into the inside thereof. The first outer electrode 21 and the second outer electrode 22 are electrically connected to the coil.

In the multilayer coil component 1 and the multilayer body 10 of the embodiment of the present disclosure, a length direction, a height direction, and a width direction are respectively an x direction, a y direction, and a z direction in FIG. 1. Here, the length direction (x direction), the height direction (y direction), and the width direction (z direction) are perpendicular to each other.

As illustrated in FIGS. 1, 2A, 2B, and 2C, the multilayer body 10 has a first end surface 11 and a second end surface 12, which face each other in the length direction (x direction), a first main surface 13 and a second main surface 14, which face each other in the height direction (y direction) perpendicular to the length direction, and a first side surface 15 and a second side surface 16, which face each other in the width direction (z direction) perpendicular to the length direction and the height direction.

Although not illustrated in FIG. 1, corner portions and edge portions of the multilayer body 10 are preferably rounded. The term "corner portion" refers to a part of the multilayer body 10 where three surfaces intersect and the term "edge portion" refers to a part of the multilayer body 10 where two surfaces intersect.

The first outer electrode 21 is arranged so as to cover part of the first end surface 11 of the multilayer body 10 as illustrated in FIGS. 1 and 2B and so as to extend from the first end surface 11 and cover part of the first main surface 13 of the multilayer body 10, as illustrated in FIGS. 1 and 2C. As illustrated in FIG. 2B, the first outer electrode 21 covers a region of the first end surface 11 that includes the edge portion that intersects the first main surface 13, and may extend from the first end surface 11 so as to cover the second main surface 14.

In FIG. 2B, the height of the part of the first outer electrode 21 that covers the first end surface 11 of the multilayer body 10 is constant, but the shape of the first outer electrode 21 is not particularly limited so long as the first outer electrode 21 covers part of the first end surface 11 of the multilayer body 10. For example, the first outer electrode 21 may have an arch-like shape that increases in height from the ends thereof toward the center thereof on the first end surface 11 of the multilayer body 10. In addition, in FIG. 2C, the length of the part of the first outer electrode 21 that covers the first main surface 13 of the multilayer body 10 is constant, but the shape of the first outer electrode 21 is not particularly limited so long as the first outer electrode 21 covers part of the first main surface 13 of the multilayer body 10. For example, the first outer electrode 21 may have an arch-like shape that increases in length from the ends thereof toward the center thereof on the first main surface 13 of the multilayer body 10.

As illustrated in FIGS. 1 and 2A, the first outer electrode 21 may be additionally arranged so as to extend from the first end surface 11 and the first main surface 13 and cover part of the first side surface 15 and part of the second side surface 16. In this case, as illustrated in FIG. 2A, the parts of the first outer electrode 21 covering the first side surface 15 and the second side surface 16 are preferably formed in a diagonal shape relative to both the edge portion that intersects the first end surface 11 and the edge portion that intersects the first main surface 13. However, the first outer electrode 21 does not have to be arranged so as to cover part of the first side surface 15 and part of the second side surface 16.

The second outer electrode 22 is arranged so as to cover part of the second end surface 12 of the multilayer body 10 and so as to extend from the second end surface 12 and cover part of the first main surface 13 of the multilayer body 10.

Similarly to the first outer electrode 21, the second outer electrode 22 covers a region of the second end surface 12 that includes the edge portion that intersects the first main surface 13. In addition, similarly to the first outer electrode 21, the second outer electrode 22 may extend from the second end surface 12 and cover part of the second main surface 14, part of the first side surface 15, and part of the second side surface 16.

Similarly to the first outer electrode 21, the shape of the second outer electrode 22 is not particularly limited so long as the second outer electrode 22 covers part of the second end surface 12 of the multilayer body 10. For example, the second outer electrode 22 may have an arch-like shape that increases in height from the ends thereof toward the center thereof on the second end surface 12 of the multilayer body 10. Furthermore, the shape of the second outer electrode 22 is not particularly limited so long as the second outer electrode 22 covers part of the first main surface 13 of the multilayer body 10. For example, the second outer electrode 22 may have an arch-like shape that increases in length from the ends thereof toward the center thereof on the first main surface 13 of the multilayer body 10.

Similarly to the first outer electrode 21, the second outer electrode 22 may be additionally arranged so as to extend from the second end surface 12 and the first main surface 13 and cover part of the second main surface 14, part of the first side surface 15, and part of the second side surface 16. In this case, the parts of the second outer electrode 22 covering the first side surface 15 and the second side surface 16 are preferably formed in a diagonal shape relative to both the edge portion that intersects the second end surface 12 and the edge portion that intersects the first main surface 13. However, the second outer electrode 22 does not have to be arranged so as to cover part of the second main surface 14, part of the first side surface 15, and part of the second side surface 16.

The first outer electrode 21 and the second outer electrode 22 are arranged in the manner described above, and therefore the first main surface 13 of the multilayer body 10 serves as a mounting surface when the multilayer coil component 1 is mounted on a substrate.

Although the size of the multilayer coil component 1 according to the embodiment of the present disclosure is not particularly limited, the multilayer coil component 1 is preferably the 0603 size, the 0402 size, or the 1005 size.

In the case where the multilayer coil component 1 according to the embodiment of the present disclosure is the 0603 size, the length of the multilayer body 10 (length indicated by double-headed arrow L_1 in FIG. 2A) preferably lies in a range from 0.57 mm to 0.63 mm and more preferably lies in a range from 0.56 mm (560 μ m) to 0.60 mm (600 μ m). In the case where the multilayer coil component 1 according to the embodiment of the present disclosure is the 0603 size, the width of the multilayer body 10 (length indicated by double-headed arrow W_1 in FIG. 2C) preferably lies in a range from 0.27 mm to 0.33 mm. In the case where the multilayer coil component 1 according to the embodiment of the present disclosure is the 0603 size, the height of the multilayer body 10 (length indicated by double-headed arrow T_1 in FIG. 2B) preferably lies in a range from 0.27 mm to 0.33 mm.

In the case where the multilayer coil component 1 according to the embodiment of the present disclosure is the 0603 size, the length of the multilayer coil component 1 (length indicated by double arrow L_2 in FIG. 2A) preferably lies in a range from 0.57 mm to 0.63 mm. In the case where the multilayer coil component 1 according to the embodiment of the present disclosure is the 0603 size, the width of the

multilayer coil component **1** (length indicated by double-headed arrow W_2 in FIG. 2C) preferably lies in a range from 0.27 mm to 0.33 mm In the case where the multilayer coil component **1** according to the embodiment of the present disclosure is the 0603 size, the height of the multilayer coil component **1** (length indicated by double-headed arrow T_2 in FIG. 2B) preferably lies in a range from 0.27 mm to 0.33 mm.

In the case where the multilayer coil component **1** according to the embodiment of the present disclosure is the 0603 size, the length of the part of the first outer electrode **21** that covers the first main surface **13** of the multilayer body **10** (length indicated by double-headed arrow E_1 in FIG. 2C) preferably lies in a range from 0.12 mm to 0.22 mm Similarly, the length of the part of the second outer electrode **22** that covers the first main surface **13** of the multilayer body **10** preferably lies in a range from 0.12 mm to 0.22 mm Additionally, in the case where the length of the part of the first outer electrode **21** that covers the first main surface **13** of the multilayer body **10** and the length of the part of the second outer electrode **22** that covers the first main surface **13** of the multilayer body **10** are not constant, it is preferable that the lengths of the longest parts thereof lie within the above-described range.

In the case where the multilayer coil component **1** according to the embodiment of the present disclosure is the 0603 size, the height of the part of the first outer electrode **21** that covers the first end surface **11** of the multilayer body **10** (length indicated by double-headed arrow E_2 in FIG. 2B) preferably lies in a range from 0.10 mm to 0.20 mm. Similarly, the height of the part of the second outer electrode **22** that covers the second end surface **12** of the multilayer body **10** preferably lies in a range from 0.10 mm to 0.20 mm. In this case, stray capacitances arising from the outer electrodes **21** and **22** can be reduced. In the case where the height of the part of the first outer electrode **21** that covers the first end surface **11** of the multilayer body **10** and the height of the part of the second outer electrode **22** that covers the second end surface **12** of the multilayer body **10** are not constant, it is preferable that the heights of the highest parts thereof lie within the above-described range.

In the case where the multilayer coil component **1** according to the embodiment of the present disclosure is the 0402 size, the length of the multilayer body **10** preferably lies in a range from 0.38 mm to 0.42 mm and the width of the multilayer body **10** preferably lies in a range from 0.18 mm to 0.22 mm In the case where the multilayer coil component **1** according to the embodiment of the present disclosure is the 0402 size, the height of the multilayer body **10** preferably lies in a range from 0.18 mm to 0.22 mm.

In the case where the multilayer coil component **1** according to the embodiment of the present disclosure is the 0402 size, the length of the multilayer coil component **1** preferably lies in a range from 0.38 mm to 0.42 mm In the case where the multilayer coil component **1** according to the embodiment of the present disclosure is the 0402 size, the width of the multilayer coil component **1** preferably lies in a range from 0.18 mm to 0.22 mm In the case where the multilayer coil component **1** according to the embodiment of the present disclosure is the 0402 size, the height of the multilayer coil component **1** preferably lies in a range from 0.18 mm to 0.22 mm.

In the case where the multilayer coil component **1** according to the embodiment of the present disclosure is the 0402 size, the length of the part of the first outer electrode **21** that covers the first main surface **13** of the multilayer body **10** preferably lies in a range from 0.08 mm to 0.15 mm.

Similarly, the length of the part of the second outer electrode **22** that covers the first main surface **13** of the multilayer body **10** preferably lies in a range from 0.08 mm to 0.15 mm.

In the case where the multilayer coil component **1** according to the embodiment of the present disclosure is the 0402 size, the height of the part of the first outer electrode **21** that covers the first end surface **11** of the multilayer body **10** preferably lies in a range from 0.06 mm to 0.13 mm Similarly, the height of the part of the second outer electrode **22** that covers the second end surface **12** of the multilayer body **10** preferably lies in a range from 0.06 mm to 0.13 mm In this case, stray capacitances arising from the outer electrodes **21** and **22** can be reduced.

In the case where the multilayer coil component **1** according to the embodiment of the present disclosure is the 1005 size, the length of the multilayer body **10** preferably lies in a range from 0.95 mm to 1.05 mm and the width of the multilayer body **10** preferably lies in a range from 0.45 mm to 0.55 mm In the case where the multilayer coil component **1** according to the embodiment of the present disclosure is the 1005 size, the height of the multilayer body **10** preferably lies in a range from 0.45 mm to 0.55 mm.

In the case where the multilayer coil component **1** according to the embodiment of the present disclosure is the 1005 size, the length of the multilayer coil component **1** preferably lies in a range from 0.95 mm to 1.05 mm In the case where the multilayer coil component **1** according to the embodiment of the present disclosure is the 1005 size, the width of the multilayer coil component **1** preferably lies in a range from 0.45 mm to 0.55 mm In the case where the multilayer coil component **1** according to the embodiment of the present disclosure is the 1005 size, the height of the multilayer coil component **1** preferably lies in a range from 0.45 mm to 0.55 mm.

In the case where the multilayer coil component **1** according to the embodiment of the present disclosure is the 1005 size, the length of the part of the first outer electrode **21** that covers the first main surface **13** of the multilayer body **10** preferably lies in a range from 0.20 mm to 0.38 mm. Similarly, the length of the part of the second outer electrode **22** that covers the first main surface **13** of the multilayer body **10** preferably lies in a range from 0.20 mm to 0.38 mm.

In the case where the multilayer coil component **1** according to the embodiment of the present disclosure is the 1005 size, the height of the part of the first outer electrode **21** that covers the first end surface **11** of the multilayer body **10** preferably lies in a range from 0.15 mm to 0.33 mm. Similarly, the height of the part of the second outer electrode **22** that covers the second end surface **12** of the multilayer body **10** preferably lies in a range from 0.15 mm to 0.33 mm In this case, stray capacitances arising from the outer electrodes **21** and **22** can be reduced.

The coil that is built into the multilayer body **10** of the multilayer coil component **1** according to the embodiment of the present disclosure will be described next. The coil is formed by electrically connecting a plurality of coil conductors, which are stacked in the length direction together with the insulating layers, to one another.

FIG. 3 is a sectional view schematically illustrating an example of the multilayer coil component **1** according to the embodiment of the present disclosure and FIG. 4 is an exploded perspective view schematically illustrating the state of the insulating layers of the multilayer coil component **1** illustrated in FIG. 3. FIG. 3 illustrates insulating layers, coil conductors, connection conductors, and a stacking direction of the multilayer body **10** in a schematic manner, and the actual shapes, connections, and so forth are

not depicted with strict accuracy. For example, the coil conductors are connected to each other by via conductors. The stacking direction of the multilayer body 10 and the axial direction of the coil (coil axis is denoted by A in FIG. 3) are parallel to the first main surface 13, which is the mounting surface.

As illustrated in FIG. 3, the multilayer coil component 1 includes the multilayer body 10, which has a coil built into the inside thereof, that is formed by electrically connecting together a plurality of coil conductors 32 that are stacked together with insulating layers; and the first outer electrode 21 and the second outer electrode 22, which are electrically connected to the coil. The multilayer body 10 includes a region 10a in which the coil conductors 32 are arranged and regions 10b in which a first connection conductor 41 and a second connection conductor 42 are arranged. The stacking direction of the multilayer body 10 and the axial direction of the coil (coil axis A illustrated in FIG. 3) are parallel to the first main surface 13, which is the mounting surface.

A length L_3 of the region 10a in which the coil conductors 32 are arranged in the stacking direction lies in a range from 85% to 95% (90% in FIG. 3) of the length L_1 of the multilayer body 10. When the length of the region 10a in which the coil conductors 32 are arranged in the stacking direction lies in a range from 85% to 95% of the length of the multilayer body 10, a high inductance can be exhibited.

A distance D between coil conductors 32 that are adjacent to each other in the stacking direction of the multilayer body 10 lies in a range from 12 μm to 40 μm . When the distance D between coil conductors 32 that are adjacent to each other in the stacking direction of the multilayer body 10 lies in the range from 12 μm to 40 μm , the radio-frequency characteristics are improved. When the distance D between coil conductors 32 that are adjacent to each other in the stacking direction is less than 12 μm , stray capacitances increase and the radio-frequency characteristics are degraded. On the other hand, when the distance D between coil conductors 32 that are adjacent to each other in the stacking direction exceeds 40 μm , the inductance of the coil decreases.

When the length of the region 10a in which the coil conductors 32 are arranged in the stacking direction lies in the range from 85% to 95% of the length of the multilayer body 10 and the distance D between coil conductors 32 that are adjacent to each other in the stacking direction lies in the range from 12 μm to 40 μm , stray capacitances are reduced, and therefore the radio-frequency characteristics can be improved and the transmission coefficient S21 at 60 GHz can be made to be greater than or equal to -2 dB. In the case where the transmission coefficient S21 of the multilayer coil component 1 at 60 GHz is greater than or equal to -2 dB, for example, the multilayer coil component 1 can be suitably used in a bias-tee circuit inside an optical communication circuit. The transmission coefficient S21 is obtained from the ratio of the power of a transmitted signal to the power of an input signal. The transmission coefficient S21 at each frequency can be obtained using a network analyzer, for example. The transmission coefficient S21 is basically a dimensionless quantity, but is usually expressed in dB using the common logarithm.

As illustrated in FIG. 4, the multilayer body 10 is formed by stacking a plurality of insulating layers 35a (35a₁ and 35a₂), 31a, 31b, 31c, 31d, 31e, and 35b (35b₁ and 35b₂) in the length direction (x direction). The direction in which the plurality of insulating layers of the multilayer body 10 are stacked is called the stacking direction. In other words, in the multilayer coil component 1 of the embodiment of the

present disclosure, the length direction of the multilayer body 10 and the stacking direction of the insulating layers match each other.

Coil conductors 32a, 32b, 32c, and 32d and via conductors 33a, 33b, 33c, and 33d are respectively provided on and in the insulating layers 31a, 31b, 31c, and 31d. The coil conductors 32a, 32b, 32c, and 32d each include a line portion and land portions disposed at the ends of the line portion. As illustrated in FIG. 4, it is preferable the land portions be slightly larger than the line width of the line portions.

The coil conductors 32a, 32b, 32c, and 32d are respectively provided on main surfaces of the insulating layers 31a, 31b, 31c, and 31d and are stacked together with the insulating layers 31a, 31b, 31c, 31d, and 31e. In FIG. 4, each coil conductor is shaped so as to extend through $\frac{3}{4}$ of a turn and the insulating layers 31a, 31b, 31c, and 31d are repeatedly stacked as one unit (three turns). The insulating layers 31a, 31b, 31c, and 31d are not stacked directly adjacent to each other but rather are stacked with the insulating layers 31e interposed therebetween.

The via conductors 33g, 33a, 33b, 33c, 33d, 33e, and 33h are provided so as to respectively penetrate through the insulating layers 35a (35a₁ and 35a₂), 31a, 31b, 31c, 31d, 31e, and 35b (35b₁ and 35b₂) in the stacking direction (x direction in FIG. 4).

The thus-configured insulating layers 35a₁, 35a₂, 31a, 31b, 31c, 31d, 31e, 35b₁, and 35b₂ are stacked in the x direction as illustrated in FIG. 4. Two insulating layers 31e are arranged between the insulating layers 31a and 31b, between the insulating layers 31b and 31c, and between the insulating layers 31c and 31d. In addition, in the case where the insulating layers 31a, 31b, 31c, and 31d are repeatedly stacked in this order, two insulating layers 31e are also stacked between the insulating layers 31d and 31a. Therefore, the land portions of coil conductors 32 that are adjacent to each other in the stacking direction are connected to each other by a plurality of via conductors (three in FIG. 4) that are connected to each other in the stacking direction. As a result, a solenoid coil having a coil axis that extends in the x direction is formed inside the multilayer body 10.

On the other hand, the via conductors 33g and 33h form connection conductors inside the multilayer body 10 and are exposed at the two end surfaces 11 and 12 of the multilayer body 10. As described later, the connection conductors are formed inside the multilayer body 10 by the via conductors 33g being connected in a straight line between the first outer electrode 21 and the coil conductor 32a that faces the first outer electrode 21 and the via conductors 33h being connected in a straight line between the second outer electrode 22 and the coil conductor 32d that faces the second outer electrode 22.

The coil conductors 32 forming the coil preferably overlap in a plan view from the stacking direction. In addition, the coil preferably has a substantially circular shape in a plan view from the stacking direction. In the case where the coil includes land portions, the shape of the coil is taken to be the shape obtained by removing the land portions (i.e., the shape of the line portions). In addition, in the case where land portions are connected to the via conductors forming the connection conductors, the shape of the connection conductors is the shape obtained by removing the land portions (i.e., the shape of the via conductors).

The phrase "the first connection conductor 41 is connected in a straight line between the first outer electrode 21 and the coil" means that the via conductors 33g forming the first connection conductor 41 overlap one another in a plan

view from the stacking direction and it is not necessary for the via conductors 33g to be perfectly arranged in a straight line. In addition, the phrase "the second connection conductor 42 is connected in a straight line between the second outer electrode 22 and the coil" means that the via conductors 33h forming the second connection conductor 42 overlap one another in a plan view from the stacking direction and it is not necessary for the via conductors 33h to be perfectly arranged in a straight line. In the case where land portions are connected to the via conductors forming the connection conductors, the shape of the connection conductors is the shape obtained by removing the land portions (i.e., the shape of the via conductors).

The coil conductors illustrated in FIG. 4 are shaped so that the repeating pattern has a substantially circular shape, but the coil conductors may instead be shaped so that the repeating pattern has a substantially polygonal shape such as a substantially quadrangular shape. In addition, the repeating shape of the coil conductors may be a $\frac{1}{2}$ turn shape rather than a $\frac{3}{4}$ turn shape. In the case where the coil has a substantially polygonal shape in a plan view from the stacking direction, the coil diameter is the diameter of an area-equivalent circle of the polygonal shape and the coil axis is an axis that extends in the stacking direction through the center of the polygonal shape.

In a plan view from the stacking direction, the line width of the line portions of the coil conductors preferably lies in a range from 30 μm to 80 μm and more preferably lies in the range from 30 μm to 60 μm . In the case where the line width of the line portions is smaller than 30 μm , the direct-current resistance of the coil may be large. In the case where the line width of the line portions is larger than 80 μm , the electrostatic capacitance of the coil may be large, and therefore the radio-frequency characteristics of the multilayer coil component 1 may be degraded.

In a plan view from the stacking direction, in each coil conductor, the outer periphery of each land portion preferably contacts the inner periphery of the line portion. With this configuration, the area of the land portion located outside the outer periphery of the line portion is sufficiently small and a stray capacitance arising from the land portion is small, and therefore the radio-frequency characteristics of the multilayer coil component 1 are further improved.

The shape of the land portions in a plan view from the stacking direction may be a substantially circular shape or may be a substantially polygonal shape. In the case where the shape of the land portions is a substantially polygonal shape, the diameter of the land portions is taken to be the diameter of an area-equivalent circle of the polygonal shape.

The thickness of the coil conductors is not particularly limited, but preferably lies in a range from 3 μm to 6 μm .

The diameter of the land portions is not particularly limited, but preferably lies in a range from 20 μm to 40 μm . When the diameter of the land portions is less than 20 μm , the diameter of the via conductors may become too small and the electrical resistance between coil conductors may become too large. On the other hand when the diameter of the land portions is greater than 40 μm , a stray capacitance may become too large and the radio-frequency characteristics may be degraded.

The taper angle of the via conductors is not particularly limited, but preferably lies in a range from 60° to 120°. The taper angle of a via conductor is an angle at which extension lines extending from both end surfaces of the via conductor intersect each other when both side surfaces of the via conductor are extended in a cross section obtained by cutting the multilayer body in the stacking direction. When the taper

angle lies in the range from 60° to 120°, the via conductors can be formed without making the land portions large, and therefore stray capacitances can be suppressed and the radio-frequency characteristics can be improved.

5 In the multilayer coil component 1 according to the embodiment of the present disclosure, the thickness of the insulating layers is not particularly limited, but preferably lies in a range from 3 μm to 10 μm . In addition, in the case where the thickness of the insulating layers is greater than 10 μm , it may be necessary to make the land portions larger in order to connect coil conductors that are adjacent to each other in the stacking direction and stray capacitances may increase. On the other hand, in the case where the thickness of the insulating layers is less than 3 μm , the insulating layers may become too thin, variations may occur in the thicknesses of the insulating layers, and the characteristics of the coil may be degraded.

10 In the multilayer coil component 1 according to the embodiment of the present disclosure, the land portions of 20 coil conductors that are adjacent to each other in the stacking direction are preferably connected to each other by a plurality of via conductors connected together in the stacking direction. When the land portions of coil conductors that are adjacent to each other in the stacking direction are connected 25 to each other by a plurality of via conductors connected together in the stacking direction, the distance between the coil conductors can be increased without increasing the size of the land portions.

15 In order to connect the land portions of coil conductors 30 that are adjacent to each other in the stacking direction using a plurality of via conductors connected together in the stacking direction, a method may be used in which insulating layers in which only via conductors are provided are stacked between insulating layers on which coil conductors 35 are provided, rather than stacking only insulating layer on which coil conductors are provided. The insulating layers on which coil conductors are provided and the insulating layers in which only via conductors are provided may have identical thicknesses or may have different thicknesses.

20 The multilayer coil component 1 of the embodiment of the present disclosure is preferably configured so that the land portions are not positioned inside the inner periphery of the line portions and partially overlap the line portions in a plan view from the stacking direction. If the land portions 45 are positioned inside the inner periphery of the line portions, the impedance may undesirably decrease. In addition, it is preferable that the diameter of the land portions lie in a range from 1.05 to 1.6 times the line width of the line portions and more preferably 1.05 to 1.3 times the line width of the line portions in a plan view from the stacking direction. When the diameter of the land portions is less than 1.05 times the line width of the line portions, the connections between the land portions and the via conductors may be unsatisfactory. On the other hand, if the diameter of the land portions is 55 greater than 1.6 times the line width of the line portions, the radio-frequency characteristics may be degraded due to the stray capacitances arising from the land portions becoming larger.

25 In the present specification, the distance D between coil conductors 32 that are adjacent to each other in the stacking direction is the shortest distance in the stacking direction between the coil conductors 32 that are connected to each other by via conductors. Therefore, the distance D between coil conductors 32 that are adjacent to each other in the stacking direction and the distance between coil conductors 32 that cause stray capacitances to be generated are not necessarily the same.

11

FIG. 5 is an enlarged sectional view of a region where coil conductors 32 are connected to each other. As illustrated in FIG. 5, when a region where coil conductors 32 are connected to each other is viewed in a cross section obtained by cutting the multilayer body 10 along the length direction of the multilayer body 10, the coil conductors 32a and 32b are connected to each other by a plurality (three in FIG. 5) of via conductors 33a, 33e, and 33e that are connected together in the stacking direction and the distance between the coil conductors 32a and 32b that are adjacent to each other in the stacking direction is represented by D. The via conductors 33a, 33e, and 33e have a taper angle of 90°. When the coil conductors are connected to each other by a plurality of via conductors that are connected together in the stacking direction, the size of the land portions can be reduced compared with the case where coil conductors are connected to each other using a single via conductor.

In the multilayer coil component 1 according to the embodiment of the present disclosure, the mounting surface is not particularly limited, but it is preferable that the first main surface 13 be the mounting surface.

Specific examples of the preferred dimensions of the coil conductors and connection conductors will be described hereafter for cases where the size of the multilayer coil component 1 is the 0603 size, the 0402 size, and the 1005 size.

1. Multilayer Coil Component 1 is 0603 Size

The inner diameter (coil diameter) of each coil conductor preferably lies in a range from 50 μm to 100 μm in a plan view from the stacking direction.

The length of each connection conductor preferably lies in a range from 15 μm to 45 μm and more preferably lies in a range from 15 μm to 30 μm .

The width of each connection conductor preferably lies in a range from 30 μm to 60 μm .

2. Multilayer Coil Component 1 is 0402 Size

The inner diameter (coil diameter) of each coil conductor preferably lies in a range from 30 μm to 70 μm in a plan view from the stacking direction.

The length of each connection conductor preferably lies in a range from 10 μm to 30 μm and more preferably lies in a range from 10 μm to 25 μm .

The width of each connection conductor preferably lies in a range from 20 μm to 40 μm .

3. Multilayer Coil Component 1 is 1005 Size

The inner diameter (coil diameter) of each coil conductor preferably lies in a range from 80 μm to 170 μm in a plan view from the stacking direction.

The length of each connection conductor preferably lies in a range from 25 μm to 75 μm and more preferably lies in a range from 25 μm to 50 μm .

The width of each connection conductor preferably lies in a range from 40 μm to 100 μm .

Method of Manufacturing Multilayer Coil Component

Hereafter, an example of a method of manufacturing a multilayer coil component according to an embodiment of the present disclosure will be described.

First, ceramic green sheets, which will later form the insulating layers, are manufactured. For example, an organic binder such as a polyvinyl butyral resin, an organic solvent such as ethanol or toluene, and a dispersant are added to a ferrite material and the resulting mixture is kneaded to form a slurry. After that, ceramic green sheets having a thickness of around 12 μm are manufactured using a method such as a doctor blade technique.

The ferrite material may be manufactured using the following method, for example. First, iron, nickel, zinc, and

12

copper oxide materials are mixed together and calcined at 800° C. for one hour. After that, manufacture of a Ni—Zn—Cu ferrite material (oxide mixed powder) having an average particle diameter of 2 μm is completed by pulverizing the obtained calcined material with a ball mill and then drying the material.

When manufacturing the ceramic green sheets using a ferrite material, it is preferable that the composition of the ferrite material consist of Fe_2O_3 in a range from 40 mol % to 49.5 mol %, ZnO in a range from 5 mol % to 35 mol %, CuO in range from 4 mol % to 12 mol %, and the remainder consisting of NiO and trace amounts of additives (including inevitable impurities) in order to realize a high inductance.

As a ceramic green sheet material, other than a magnetic material such as the ferrite material described above, for example, a non-magnetic material such as a glass ceramic material or a mixed material consisting of a magnetic material and a non-magnetic material may be used.

Next, conductor patterns that will later form the coil conductors and via conductors are formed on and in the ceramic green sheets. For example, first, via holes having a diameter of around 20 μm to 30 μm are formed by subjecting the ceramic green sheets to laser processing. Then, via-conductor conductor patterns are formed by filling the via holes with a conductive paste such as silver paste. In addition, coil-conductor conductor patterns having a thickness of around 11 μm are formed via printing using a method such as screen printing using a conductive paste such as silver paste on main surfaces of the ceramic green sheets.

For example, conductor patterns and so on corresponding to the coil conductors illustrated in FIG. 4 are formed as the coil-conductor conductor patterns by performing printing.

Next, drying is performed, and as a result coil sheets having a configuration in which the coil-conductor conductor patterns and the via-conductor conductor patterns are formed on and in ceramic green sheets are obtained. The coil-conductor conductor patterns and the via-conductor conductor patterns are connected to each other in the coil sheets.

Furthermore, via sheets that have a configuration in which via-conductor conductor patterns are formed are manufactured separately from the coil sheets. The via-conductor conductor patterns of the via sheets are conductor patterns that will later form the via conductors constituting the connection conductors.

Next, the coil sheets are stacked in a prescribed order so that a coil having a coil axis that is parallel to the mounting surface will be formed inside the multilayer body after division into individual components and firing. At this time, at least one via sheet is interposed between each pair of coil sheets. The number of via sheets interposed between each pair of coil sheets preferably lies in a range from 1 to 7 and more preferably lies in a range from 2 to 4. The thickness of the via sheets may be the same as that of the coil sheets or may be different from that of the coil sheets. In addition, via sheets are stacked above and below the multilayer body formed of the coil sheets.

The multilayer body consisting of the coil sheets and the via sheets is subjected to thermal pressure bonding in order to obtain a pressure-bonded body, and then the pressure-bonded body is cut into pieces of a predetermined chip size to obtain individual chips. The divided chips may be subjected to barrel polishing in order to round the corner portions and edge portions thereof.

Next, the divided chips are subjected to binder removal and firing at a prescribed temperature and for a prescribed period of time, and multilayer bodies (fired bodies) having

a built-in coil are formed. At this time, the coil-conductor conductor patterns and the via-conductor conductor patterns become the coil conductors and the via conductors after firing. The coil is formed by the coil conductors being connected to one another by the via conductors. In addition, the stacking direction of the multilayer body and the coil axis direction of the coil are parallel to the mounting surface.

Next, a conductive paste such as silver paste is spread so as to form a layer of a predetermined thickness and then each multilayer body is dipped at an angle into this layer and baked to form a base electrode layer of an outer electrode on four surfaces (a main surface, an end surface, and both side surfaces) of the multilayer body. Using this method, the base electrode can be formed in one go in contrast to the case where the base electrode is formed separately on the main surface and the end surface of the multilayer body in two steps. A base electrode of an outer electrode can be formed on five surfaces of the multilayer body (four surfaces consisting of adjacent main surfaces and side surfaces in addition to the respective end surface) when a method is used in which a chip is vertically dipped in a layer formed by spreading silver paste to a prescribed thickness.

Next, a nickel film and a tin film having predetermined thicknesses are formed on the base electrode layers by performing plating. Thus, the outer electrodes are formed.

A multilayer coil component according to an embodiment of the present disclosure can be manufactured as described above.

EXAMPLES

Hereafter, examples that illustrate the multilayer coil component 1 according to the embodiment of the present disclosure in a more specific manner will be described. The present disclosure is not limited to just the following examples.

Manufacture of Test Pieces

Example 1

1. A ferrite material (calcined powder) having a prescribed composition was prepared.

2. A magnetic slurry was manufactured by adding an organic binder (polyvinyl butyral resin) and organic solvents (ethanol and toluene) to the calcined powder and putting the mixture into a pot mill along with PSZ balls and then sufficiently mixing and pulverizing the mixture in a wet state.

3. The magnetic slurry was formed into a sheet using a doctor blade method and punched into rectangular shapes, thereby producing a plurality of ceramic green sheets having a thickness of 12 μm .

4. An inner-conductor conductive paste containing Ag powder and an organic vehicle was prepared.

5. Via Sheet Manufacture

Via holes were formed by irradiating prescribed locations on the ceramic green sheets with a laser. Via conductors were formed by filling the via holes with a conductive paste and land portions were formed by performing screen printing with a conductive paste in circular shapes around the peripheries of the via conductors.

6. Coil Sheet Manufacture

The coil sheets were obtained by forming via conductors by forming via holes in prescribed locations on the ceramic green sheets and filling the via holes with a conductive paste, and then forming coil conductors including land portions and line portions by performing printing.

7. These sheets were stacked in the order illustrated in FIG. 4 with the number of via sheets interposed between each pair of coil sheets changed to one via sheet, and then heated, pressed, and cut into individual pieces with a dicer to form multilayer molded bodies.

8. (Fired) multilayer bodies were manufactured by placing the multilayer molded bodies in a firing furnace, subjecting the bodies to a binder removal treatment under an air atmosphere at a temperature of 500°C. and then firing the bodies at a temperature of 900°C. The dimensions of thirty of the obtained multilayer bodies were measured using a micrometer, and the following average values were determined: L=0.60 mm, W=0.30 mm, and T=0.30 mm.

9. An outer-electrode conductive paste containing Ag powder and glass frit was poured into a coating film forming tank in order to form a coating film of a predetermined thickness. The places where the outer electrodes are to be formed on each multilayer body were immersed in the coating film.

10. After the immersion, each multilayer body was baked at a temperature of around 800°C. and in this way the base electrodes of the outer electrodes were formed.

11. Formation of the outer electrodes was completed by sequentially forming a Ni film and a Sn film on the base electrodes by performing electroplating. Test pieces of example 1 having the internal structure of the multilayer body 10 illustrated in FIG. 3 were manufactured as described above. In the test pieces of example 1, the length of the region in which the coil conductors 32 are arranged in the stacking direction was 93.1% of the length of the multilayer body 10 and the distance D between coil conductors 32 that are adjacent to each other in the stacking direction was 12.7 μm .

Measurement of Transmission Coefficient S21

35 FIG. 6 is a diagram schematically illustrating a method of measuring the transmission coefficient S21. As illustrated in FIG. 6, a test piece (multilayer coil component 1) was soldered to a measurement jig 60 that was provided with a signal path 61 and a ground conductor 62. The first outer electrode 21 of the multilayer coil component 1 was connected to the signal path 61 and the second outer electrode 22 of the multilayer coil component 1 was connected to the ground conductor 62.

40 The transmission coefficient S21 was measured by obtaining the power of an input signal to the test piece and the power of a transmitted signal from the test piece and changing the signal frequency using a network analyzer 63. The two ends of the signal path 61 are connected to the network analyzer 63. The measurement results are illustrated in FIG. 7 and the respective transmission coefficients S21 at 60 GHz are illustrated in Table 1. FIG. 7 is a graph illustrating the transmission coefficients S21 of test pieces manufactured in examples. The transmission coefficient S21 indicates that the closer the transmission coefficient S21 is to 0 dB, the smaller the loss is.

Examples 2 to 5 and Comparative Examples 1 and 2

60 As illustrated in Table 1, multilayer coil components according to examples 2 to 5 and comparative examples 1 and 2 were manufactured using the same procedure as described in example 1 except that the distance between coil conductors that are adjacent to each other in the stacking direction was changed as illustrated in Table 1 by adjusting the number of via sheets and thicknesses of the via sheets arranged between the coil sheets and then the transmission

15

coefficients S21 were measured. The obtained results are illustrated in Table 1. In all the test pieces, the ratio of the length of the region in which the coil conductors are arranged in the stacking direction with respect to the length of the multilayer body was 93.1%, which is the same as in example 1.

TABLE 1

	Distance between adjacent coil conductors in stacking direction (μm)	Transmission coefficient S21 (dB) at 60 GHz
Example 1	12.7	-1.99
Example 2	15.9	-1.83
Example 3	20.4	-1.60
Example 4	27.1	-1.36
Example 5	39.1	-1.04
Comparative Example 1	6.0	-2.88
Comparative Example 2	10.4	-2.17

From the results listed in Table 1, it is clear that the multilayer coil component 1 according to the embodiment of the present disclosure has a transmission coefficient S21 that is greater than or equal to -2 dB at 60 GHz and has excellent radio-frequency characteristics.

While preferred embodiments of the disclosure have been described above, it is to be understood that variations and modifications will be apparent to those skilled in the art without departing from the scope and spirit of the disclosure. The scope of the disclosure, therefore, is to be determined solely by the following claims.

What is claimed is:

1. A multilayer coil component comprising:
a multilayer body that is formed by stacking a plurality of insulating layers on top of one another in a length direction and that has a coil built into the inside thereof; and
a first outer electrode and a second outer electrode that are electrically connected to the coil;
wherein the coil is formed by a plurality of coil conductors stacked in the length direction together with the insulating layers being electrically connected to each other,
the multilayer body has a first end surface and a second end surface, which face each other in the length direction, a first main surface and a second main surface, which face each other in a height direction perpendicular to the length direction, and a first side surface and a second side surface, which face each other in a width direction perpendicular to the length direction and the height direction,
the first outer electrode covers at least a portion of the first end surface,
the second outer electrode covers at least a portion of the second end surface,
a stacking direction of the multilayer body and a coil axis direction of the coil are parallel to the first main surface,
a length of a region in which the coil conductors are arranged in the stacking direction is in a range from 85% to 95% of a length of the multilayer body, and a distance between coil conductors that are adjacent to each other in the stacking direction is in a range from 12 μm to 40 μm.

16

2. The multilayer coil component according to claim 1, wherein

the coil conductors each include a line portion and a land portion arranged at an end of the line portion, and the land portions of coil conductors that are adjacent to each other in the stacking direction are connected to each other through via conductors.

3. The multilayer coil component according to claim 1, wherein

the land portions are not located inside an inner periphery of the line portions and partially overlap the line portions in a plan view from the stacking direction.

4. The multilayer coil component according to claim 2, wherein

a diameter of each of the land portions is in a range from 1.05 times to 1.6 times a line width of each of the line portions.

5. The multilayer coil component according to claim 2, wherein

the land portions of coil conductors that are adjacent to each other in the stacking direction are connected to each other by a plurality of via conductors that are connected together in the stacking direction.

6. The multilayer coil component according to claim 1, wherein

a thickness of each of the insulating layers is in a range from 3 μm to 10 μm.

7. The multilayer coil component according to claim 1, wherein

a thickness of each of the coil conductors is in a range from 3 μm to 6 μm.

8. The multilayer coil conductor according to claim 1, wherein

the first main surface is a mounting surface, the first outer electrode extends along and covers a portion of the first end surface and a portion of the first main surface, and

the second outer electrode extends along and covers a portion of the second end surface and a portion of the first main surface.

9. The multilayer coil component according to claim 1, wherein

the length of the multilayer body is in a range from 560 μm to 600 μm.

10. The multilayer coil component according to claim 2, wherein

the land portions are not located inside an inner periphery of the line portions and partially overlap the line portions in a plan view from the stacking direction.

11. The multilayer coil component according to claim 3, wherein

a diameter of each of the land portions is in a range from 1.05 times to 1.6 times a line width of each of the line portions.

12. The multilayer coil component according to claim 3, wherein

the land portions of coil conductors that are adjacent to each other in the stacking direction are connected to each other by a plurality of via conductors that are connected together in the stacking direction.

13. The multilayer coil component according to claim 4, wherein

the land portions of coil conductors that are adjacent to each other in the stacking direction are connected to each other by a plurality of via conductors that are connected together in the stacking direction.

17

14. The multilayer coil component according to claim **2**,
wherein

a thickness of each of the insulating layers is in a range
from 3 μm to 10 μm .

15. The multilayer coil component according to claim **3**,
wherein

a thickness of each of the insulating layers is in a range
from 3 μm to 10 μm .

16. The multilayer coil component according to claim **2**,
wherein

a thickness of each of the coil conductors is in a range
from 3 μm to 6 μm .

17. The multilayer coil component according to claim **3**,
wherein

a thickness of each of the coil conductors is in a range
from 3 μm to 6 μm .

18. The multilayer coil conductor according to claim **2**,
wherein

the first main surface is a mounting surface,

5

10

15

18

the first outer electrode extends along and covers a portion
of the first end surface and a portion of the first main
surface, and

the second outer electrode extends along and covers a
portion of the second end surface and a portion of the
first main surface.

19. The multilayer coil conductor according to claim **2**,
wherein

the first main surface is a mounting surface,
the first outer electrode extends along and covers a portion
of the first end surface and a portion of the first main
surface, and

the second outer electrode extends along and covers a
portion of the second end surface and a portion of the
first main surface.

20. The multilayer coil component according to claim **2**,
wherein

the length of the multilayer body is in a range from 560
 μm to 600 μm .
